UNITED STATES PATENT OFFICE.

BARTON J. PARKER, OF HOUSTON, TEXAS.

CEMENT AND CONCRETE CONSTRUCTION.

1,280,530.

Specification of Letters Patent.

Patented Oct. 1, 1918.

Application filed December 23, 1916. Serial No. 138,616.

To all whom it may concern:

Be it known that I, BARTON J. PARKER, a citizen of the United States, residing at Houston, in the county of Harris and State 5 of Texas, have invented certain new and useful Improvements in Cement and Concrete Constructions, of which the following is a specification.

This invention relates to new and useful 10 improvements in constructions formed of cement, concrete, and other similar materials.

The object of the invention is to produce 15 a structure of reinforced cement, concrete or similar materials wherein the studding, framework, walls, ceiling and floors will all be integrally united, forming a unit.

Another feature of the invention resides 20 in the provision of a structure of the character described, wherein the walls, ceiling and floors are formed double providing air spaces therein, for the free circulation of air when the ventilators are open, and forming dead air spaces when said ventilators are 25 closed, the studding and framing being provided with perforations, spaced apart, to permit the circulation of air therethrough, and also to form a key for securing the plastic material to the framing.

30 A further feature of the invention resides in an improved method of securing the lathing, which supports the cement, concrete or other materials to the studding and framework.

35 A still further feature of the invention resides in an improved form of down spout through which the water is conducted from the roof of the structure.

With the above and other objects in view, 40 the invention has particular relation to certain novel features of construction, use and arrangement of parts, an example of which is given in this specification and illustrated in the accompanying drawings, wherein:—

45 Figure 1 is a fragmentary view, partially in section, of the structure hereinafter described.

Fig. 2 is a fragmentary perspective view of one of the walls.

50 Fig. 3 is a fragmentary vertical sectional view thereof.

Fig. 4 is a fragmentary transverse sectional view thereof.

55 Figs. 5 and 6 show perspective views of the forms of trowels which may be employed in erecting the structure.

Fig. 7 shows a fragmentary perspective view of the window casing.

Fig. 8 shows a vertical sectional view thereof.

Fig. 9 shows a finished corner of the structure.

Figs. 10 and 11 show forms of partially completed down spouts in process of construction.

Fig. 12 shows a perspective view of a section of the wall showing a means for applying the plastic material to the framing and laths, and

Fig. 13 shows an implement for applying 70 the plastic material.

Referring now more particularly to the drawings, wherein like numerals of reference designate similar parts in each of the figures, the numeral 1 refers to the foundation whereon the framework is supported. The parts of this framework are formed preferably of sheet metal formed into channels and of sufficient strength to sustain the load to be carried. The numeral 2 refers 80 to the upright studding and the numeral 3 designates the joists employed. The rafters 4 supporting the roof are also formed of similar channels and the studding, joists and rafters are provided with perforations 85 5, spaced apart to provide for air circulation as hereinafter explained. Clips or teeth 6, are stamped out from the body of the studding, joists and rafters on each side to retain the wire mesh laths 7 and 8. These 90 project through the mesh of the laths and are clenched, as shown in Fig. 3 to secure the lathing in place, said lathing, however, may be fastened in position in any other manner that may be found expedient.

In construction, the foundation is laid under all inside and outside walls, and the metal studs then set in this foundation for the first story of the structure. These studs are then secured together at their upper ends 95 by means of plates as in ordinary framing and the joists 3 placed in position. The outside lath 7 is then secured to the studding, and inclosed in cement, concrete or other similar material 9. This may be done by 100 forcing the plastic material against said lath by means of a cement gun or spray, or other desired method, preferably from the inside, the trowel 10 being held against the outside of the lath opposite the point of application and moved as the work progresses so as to stop the material which is forced through 110

the lath, thereby incasing same and giving the outside of the wall a smooth surface. The ordinary trowel, however, may be used in applying the plastic material to the lath. 5 The studding are to be also incased with the material and when completed will embody a studding of concrete reinforced by the metal channels, and the plastic material will, when a cement gun is used, blow through the 10 orifices 5 of the studding leaving them open for air circulation and also key the material to the framing. In a similar manner the plastic material is applied to the inner lathing, and when applied, trowel 11 is placed 15 between the lathing opposite the point of application. This trowel is wide enough to extend from one stud to the other and is held in position by flat springs 12, 12, which press against the outer lath, said trowel being moved as the work progresses and smoothing the inner side of the inner section 13 of the wall.

20 The ceiling, floors, partitions and roof are formed in a similar manner, it being understood of course that a cement gun or any other suitable means of application of the cement or concrete may be employed. The plastic material is applied in such a manner as to thoroughly incase the lathing, 25 studding, joists and rafters and to unite them all in one integral hollow wall of structure reinforced by means of the metal framing and lathing. Finishing coats are then, of course, applied to the outer and inner 30 surfaces of the walls to give the structure a finished appearance.

35 The window casings 14 and corner boards 15 as well as base boards and molding, are also formed of the same material as the rest 40 of the structure and made integral therewith by fastening a strip of wood (not shown) of the desired thickness on the fac- 45 ing and back from the window opening, or from the corner of the structure the desired distance and then applying the plastic ma- 50 terial until it is flush with the strip and smoothing the same off. This may be applied with a small spray or trowel or in any other practical manner and should be applied before the body of the wall has thoroughly set.

55 The structure is provided with suitable down spouts at 16 leading from the roof gutter 17 and whose lower ends 18 are turned out through the wall. These down 60 spouts are secured to the wall and are constructed by forming wire mesh into a tube as 19 and fitting the same vertically in the wall space or securing them on the side of the wall. A cylindrical trowel 20 is then let down through this tube to the bottom thereof by means of a pipe 21 to the lower end of which it is attached. The plastic material is then poured into the tube and the 65 trowel elevated up through the plastic ma-

terial which forces the same out through the wire mesh incasing the same and leaving the inside thereof smooth. Fig. 11 shows the down spout formed by securing lathing on opposite sides of studding, located close together and which are incased in the plastic material as above explained. 70

In a similar manner the walls may be formed as shown in Fig. 12 by securing the laths 7 and 8 on opposite sides of the studding as hereinbefore explained, and using a suitably shaped trowel 22 in the same manner as in the construction of the down spout. 75

The structure is provided at its base with a suitable ventilator 23 which may be opened and closed in the usual way, admitting air into the basement which passes through the openings 24 into the air spaces in the walls and circulates through said 80 85 passes freely passing through the orifices 5.

In cold weather on account of the dead air in the hollow of the wall, the inner surface of the wall will not be subject to sudden changes in the temperature and consequently the moisture in the air in the 90 building will not be condensed upon the walls causing "sweating" thereof as in the case of solid concrete walls.

A structure of the character described 95 will be of cheap and easy construction as well as fire proof and sanitary.

The principle of construction hereinbefore explained is also applied in the construction of ships, barges and other marine 100 work. In this character of work the air spaces between the walls are very important, reducing the weight, and the double walls reinforced by the frame work integral therewith, give great rigidity to the structure. 105 In marine construction the joists and studs, hereinbefore referred to, become ribs, and have no perforations, so that in case the outside wall is punctured, the inner wall will hold and only one compartment will be filled 110 with water.

What I claim is:

1. The method of producing a cellular structure of reinforced concrete which consists in first outlining a structure with a metallic frame of wholly or partly foraminous reinforcing material, providing in one or in a plurality of juxtaposed continuous cells a structure of the desired shape, second, in embedding the said reinforcing frame in a monolithic mass of concrete by means of a mandrel-like tool continuously supplied with concrete and drawn through the cell passages from end to end, thereby forcing the concrete through and into intimate contact with all the parts of the frame and in then troweling the exuding keys into a unitary mass supplemented where necessary by additional concrete. 115 120 125

2. The art of making hollow walled struc- 130

tures which consists in erecting a light, self-supporting reinforce frame, comprising main members suitably disposed with sheets of reticulated material positioned on opposite sides thereof, introducing a mandrel like cement feeding member between the sheets; in feeding and forcing cement against the sheets and main members and through the reticulations by movement of the mandrel-like member and troweling the exuding keys supplemented where necessary by additional concrete whereby the entire frame is embedded in cement thereby forming a monolithic construction.

3. The process of constructing a hollow body which comprises the erection of a wholly or partially foraminous structure of the shape of the body to be constructed, applying a combined mortar supplying and smoothing implement at one end of the foraminous structure and adjacent the walls thereof on all sides, moving said implement along said structure and simultaneously and progressively causing mortar to be supplied by said implement whereby said mortar is caused to extrude through the foraminations in said body, then causing the exuding keys supplemented where necessary by additional concrete.

4. The process of constructing a hollow body which comprises the erection of a

wholly or partially foraminous structure of the shape of the body to be constructed, applying a combined mortar supplying and smoothing implement at one end of the foraminous structure and adjacent the walls thereof on all sides, moving said implement along said structure and simultaneously and progressively causing mortar to be supplied by said implement whereby said mortar is caused to extrude through the foraminations in said body, then causing the exuding keys to be united forming an integral mass.

5. The art of making hollow walled structures which consists in erecting a light, self-supporting reinforce frame, comprising main members suitably disposed with sheets of reticulated material positioned on opposite sides thereof to form continuous cells, introducing a mandrel-like member between the sheets; in feeding and forcing cement against the sheets and main members and by movement of the mandrel-like member causing the cement to exude through the foraminations to form united exuding keys.

In testimony whereof I have signed my name to this specification in the presence of two subscribing witnesses.
